(57) **CLAIM**

The ornamental design for a bed, as shown and described.

DESCRIPTION

FIG. 1 is a front elevation view of a bed showing my new design, having headboard and headrail, footrail and side rails, with carved corner posts.

FIG. 2 is a side elevational view thereof, the opposite side elevation being a mirror image.

FIG. 3 is a back elevation thereof, showing details of the headboard.

FIG. 4 is an top plan view thereof, with the head of the bed being at the left and the foot of the bed at the right; and, FIG. 5 is a perspective view thereof.

The bottom of the bed is plain and unadorned, and does not form a part of my design.
